(57) **CLAIM**

The ornamental design for a large format container, as shown and described.

DESCRIPTION

FIG. 1 is a front view of a large format container showing our new design (the rear side is the same);

FIG. 2 is a right side view thereof (the left side is the same);

FIG. 3 is to top side plan view thereof; and,

FIG. 4 is a perspective view of the front side, right side and top side thereof.

The broken lines shown in the drawings illustrate portions of the large format container that form no part of the claimed design.
